AIR PROPORTIONAL COUNTER

John A. Simpson, Jr., Chicago, Ill., assignor to
the United States of America as represented by
the United States Atomic Energy Commission

Application December 31, 1946, Serial No. 719,525

13 Claims. (Cl. 250—27.5)

1

This invention relates to an improvement in apparatus for the measurement of radioactivity. More specifically, the invention relates to an improved proportional counter for the measurement of alpha particle emission from radioactive samples.

In the counting of alpha particles emitted from a radioactive sample it is necessary to discriminate between the ionization caused by the alpha particles under measurement and ionization caused by beta particles which may likewise be emitted from the sample. This problem is particularly difficult where the beta background emanating from the sample is very high. An effective instrument for the measurement of alpha particle emission in the presence of a high beta background is the proportional counter. The ionization caused by a single alpha particle is much greater than that caused by a single beta particle. In the proportional counter the ionization induced by a charged alpha or beta particle causes further ionization by collision of the ions and electrons primarily induced with other molecules of the gas present in the counter. The total amount of ionization thus primarily and secondarily produced by a charged particle within the counter is proportional to the number of ions primarily produced. The ratio of the total amount of charge, primarily and secondarily produced by the charged particle traversing the counter and collected by the electrodes of the proportional counter, to the charge primarily produced is known as the "gas amplification factor."

Persons skilled in the art will readily understand that the term "proportional," as used herein, does not apply to amplification factors of unity, when the voltage applied between the ion-collecting electrodes is sufficient to impart to the ions created by the impinging particle velocities adequate to assure that recombination of the ions will not occur before collection, but not adequate to cause secondary ionization by the ions so primarily created, the number of ions collected by the electrodes is equal to the number of ions caused directly by the impinging particle. A device operated in such a voltage region is known as a saturated ionization chamber. The operating voltage of a proportional counter is much higher than that of a similar ionization chamber since it is necessary for proper operation of the former that the ions primarily induced be sufficiently accelerated to cause secondary ionization before being collected by the collecting electrodes.

In the proportional counter, at least one of the

electrodes is commonly in the form of a fine wire. The purpose of this design is to procure a region of extremely high field gradient surrounding this fine wire electrode. By having such a region of high electric field gradient it is possible to achieve a long chain or series of secondary ionizations (commonly called an "avalanche") from the primary ionizing event, thus greatly increasing the gas amplification factor.

The gas amplification factor of a proportional counter may be very high of the order of 10^3 or 10^4 . The gas amplification thus introduced is extremely advantageous in that the voltage signals produced by the counter are much more readily discernible from such spurious signals as microphonics, vacuum-tube noise, and stray electric fields than they are when such amplification within the gas is not present, as in an ionization chamber.

In the proportional counters heretofore used, employing gases at pressures much lower than atmospheric, for example, 6 to 9 centimeters Hg, it has been necessary to make the counter vacuum-tight. In sealing a counter so as to render it vacuum-tight it is extremely difficult at the same time to render it possible for alpha particles from a sample to be counted to enter into the active portion of the counter. As is well known in the art, alpha particles are readily absorbed by small thicknesses of almost any known material. Therefore, in the past it has usually been necessary to place the sample under measurement within the proportional counter each time that a sample was to be counted since windows sufficiently thin to admit alpha particles could not withstand the pressure differential. It is readily seen that such a procedure is not suitable for operations involving the counting of samples as a routine matter or for surveying suspected areas of, for example, laboratory equipment or portions of the human body.

Generally it is the principal object of the present invention to provide a proportional counter adapted to measure alpha particle emission from a radioactive sample without required evacuation and filling of the counter for each sample to be counted.

It is a further object to provide a proportional counter adapted to detect and measure alpha particle emission exterior to the counter.

More specifically, the object of the invention is to provide a practical proportional counter in which the ionization medium is air at atmospheric pressure.

It is a further object of the invention to provide

2

an improved center-wire suspension for proportional counters.

It is a further object of the invention to provide an air proportional counter which is not subject to spurious counts and discharges.

It is a still further object to provide an electrically conducting window in the cathode of a proportional counter.

It is a still further object of the invention to provide an improved proportional counter having parallel plate cathodes and a plurality of equally spaced anode center-wires.

The manner in which the foregoing and other objects of the invention are accomplished is illustrated in the embodiment of the attached drawing, in which:

Fig. 1 is a plan view of a proportional counter with covering screens to be described below, partially broken away to show the internal construction.

Fig. 2 is a longitudinal cross sectional view taken along the line 2—2 of Fig. 1 in the direction indicated by arrows;

Fig. 3 is a transverse cross sectional view of the proportional counter taken along the line 3—3 of Fig. 2 in the direction indicated by the arrows;

Fig. 4 is an enlarged fragmentary cross sectional view of a portion of the counter illustrated in Fig. 1, showing certain details of the mounting of the center wires thereof;

Fig. 5 is a fragmentary cross sectional view illustrating the mounting of an insulator shown in Fig. 4 taken along the line 5—5 of Fig. 4 in the direction illustrated by arrows; and

Fig. 6 is an enlarged perspective view illustrating the manner of suspension of the center-wires of the counter of Fig. 1.

Referring first to Figs. 1 and 2, a rectangular back plate 10 has mounted thereon as by screws at the outer perimeter thereof two side walls 12 and two end walls 14, for example of aluminum, defining the body of the proportional counter. The interior dimensions may be, say, 5 inches by 12 inches by $\frac{3}{8}$ inch. On the interior surface of each of the side walls 12 are two grooves 16 adapted to receive insulators 18. As appears more clearly in the transverse view of Fig. 3, each of the insulators 18 consists of a substantially rectangular bar of an insulating material, preferably polystyrene, extending across the counter from one side wall 12 to the other. Spaced along the edge of each of the insulators 18 are transverse notches 20 extending part way through the insulator. As illustrated in Fig. 3, the insulators 18 are wider at the extreme ends thereof than at the central portion in which the notches 20 appear, thus leaving air gaps 22 between the insulator 18 and the back plate 10 and between the insulator 18 and the upper conducting surface hereinafter to be described.

Centrally of the back plate 10 adjacent one end thereof is an aperture 24 (Figs. 1 and 2) through which enters the center conductor 26 of a conventional coaxial cable connector 27 which is fastened to the back plate 10 by conventional means. Two insulating posts 28, preferably of polystyrene, are equally spaced from the coaxial cable collector 27 along a transverse line slightly forward of the connector 27. The insulating posts 28, as appears more clearly in Fig. 5, are fastened to the back plate 10 by screws 30 extending therethrough, the posts 28 being internally threaded for this purpose. The

posts 28 have aligned transverse apertures therein adapted to receive in tight-fitting fashion a rod 32, for example of brass. The rod 32, for example $\frac{1}{8}$ inch in diameter, is supported transversely of the counter by the insulating posts 28. A connecting wire 34 is soldered at one end to the center conductor 26 of the connector 27 and at the other end to the central portion of the rod 32. Extending transversely of the rod 32, and thus longitudinally of the counter, are small apertures 36 in the rod 32, as clearly appears in Fig. 4.

Threaded through each of the apertures 36 is the end of a coiled spring 38. The end of each of the coiled springs 38 is prevented from coming out of the aperture 36 by a right-angle bend at the end of the spring. The other ends of the springs 38, as more clearly shown in Fig. 6, are bent into the form of small hooks 40 which support the center-wires 42 of the counter. The center-wires 42 are preferably of 1 mil tungsten wire. At each end of the wire 42 is a small conducting ball 44, preferably spherical, for example of silver solder, substantially integral with the wire 42. The ball 44 at one end of the wire 42 is retained in place by the hook 40 which is smaller in diameter than the ball 44 but greater in diameter than the wire 42. The spring 38 exerts tension on the wire 42. Each wire 42 traverses the corresponding notch 20 in the first insulator 18 and extends to the other end of the counter where the other end of the wire 42 is held in place by the other spherical ball 44 which is larger in diameter than the width of the notch 20 in the second insulator 18, so that the tension in the spring 38 holds the ball tightly against the notch 20, and thus secures the center-wire in place. It will be seen that the center-wires 42 may be readily replaced without the necessity of soldering.

Over the face of the counter, supported by the walls 12 and 14 of the counter is a rectangular frame 46 constituting the support for a window 48, which is secured, as by cement, to the edge thereof. The window 48 may be of nylon of less than 0.5 mil thickness, and preferably of 0.2 mil thickness. The window 48 extends over approximately all the face of the counter corresponding to the region between insulators 18 near either end thereof. The window 48 has deposited upon the inner surface thereof a thin coating of a conducting substance such as graphite (not visible in the drawing). Superimposed upon the frame 46 for the window 48 is an additional frame 50, preferably of a plastic such as polymerized methyl methacrylate, commonly called "lucite." The frame 50 constitutes the support for a wire mesh screen 52 preferably of stainless steel which extends thereacross and the edges of which are preferably molded into the frame 50. The frames 46 and 50 are secured to the walls 12 and 14 by screws 47 and 51, respectively. The window 48 constitutes, with the back plate 10, a parallel-plate cathode, the anode center wires 42 preferably being approximately midway therebetween. The window 48 permits alpha particles from the exterior to enter the counter. The screen 52 protects the window 48 against both protrusions and dirt accumulations on surfaces, and may readily be removed for cleaning, for example in an acid bath if made of acid-resistant materials such as suggested above.

In the construction of the counter illustrated in the drawing the joints between the various parts defining the counter body are preferably

air-permeable, for it will be readily seen that otherwise a pressure differential could be created across the delicate window 48. It is not necessary, however, to provide any aperture to allow the influx of air since in the absence of affirmative sealing means such as greases, there will be sufficient leakage between the interior of the counter and the ambient atmosphere to insure that no substantial pressure differential between the inside and the outside of the counter may exist. This will be true even with the greatest care in machining and assembling of the counter. Since it is necessary for proper operation that the counter be absolutely free of dust, it is highly desirable that the parts described above, particularly those between which air leakage will occur, be machined to the finest possible tolerances so as to allow a minimum of dust to enter the counter.

The structure of the embodiment of the present invention illustrated in the drawing having thus been described, the theory of operation and the basic principles of the design may now be discussed.

Air is admittedly not an optimum choice from the theoretical standpoint of a filling for a proportional counter. However, the use of air at atmospheric pressure as such ionization medium, as illustrated in the exemplary embodiment of the drawing, makes possible the performance of counting operations which heretofore could not adequately be performed. For example, a proportional counter such as that illustrated in the drawing may be used in making routine surveys of areas suspected of contamination by alpha particle emitting substances.

The general theory of proportional counters is well known in the art and will not be set forth here. The theory and observations below will, therefore, be confined principally to phenomena in respect to which air substantially differs from other ionizing media.

The oxygen and carbon dioxide content of air introduces the problem of negative ion formation. The electron attachment for oxygen is 1.73 electron volts. This results in serious loss of electrons formed in the primary ionization of air by an alpha particle since some of the electrons primarily induced will become attached to oxygen atoms before causing additional ionization. This is especially true in the outer, or low intensity, field region of the proportional counter. Such an effect is observed as an apparent decrease in counter efficiency. At high voltages, furthermore, this results in spurious counts since the electron which has become attached to the oxygen atom may again become detached long after the original ionizing event, and thus cause a spurious count. Although these effects are important in using such a counter as herein described for particle energy measurements, they are practically negligible for determining the number of ionizing events, as the operating voltage of the counter is selected so as to be considerably below the semi-proportional region.

The presence of nitrogen in the counter results in a relatively high operating potential. This requires that very small center-wire diameters be used in order to obtain adequate gas amplification at reasonably moderate potentials. The center-wires should therefore be less than 3 mils in diameter and preferably 1 mil or less.

In order to design air proportional counters, it is necessary to understand the principal differences between the electrical discharge mecha-

nism in a polyatomic gas and the discharge mechanism in a mixture of gases—such as air. The properties of the discharge mechanism for various types of gases used in proportional counters have been discussed in the literature of the radiation-counting art. If an alpha particle passes through a proportional counter many ion pairs are formed. In the air proportional counter a few of the electrons so liberated in the counter volume and accelerated toward the anode become attached to oxygen molecules to form negative ions, as stated above. The other electrons reach the region immediately surrounding the center-wire, and in this region of high field intensity acquire enough energy between collisions with molecules and atoms to produce ionization by collision. The threshold voltage of the proportional region is defined as the potential applied between the cathode and anode which is required to give an electron enough energy to produce ionization in its last mean-free path before being collected at the anode. An increase in the potential difference produces increasing ionization and multiplication at the center-wire.

Many of the molecules participating in the discharge become excited and, in returning to their normal state, produce photons of considerable energy.

The effect of the production of photons constitutes one of the principal differences between the discharge process in air and in a polyatomic gas. A polyatomic molecule, instead of radiating a photon, may return to its normal state by dissipating its energy in rotation or vibration levels. In addition, any photons that are produced in the polyatomic gas are necessarily of short range, because of the wide photon absorption bands in such types of molecules. In contrast to this, an air discharge produces photons of considerable range since the photon absorption of air is rather small. Under such conditions, photo-electrons may be produced at the cathode surfaces, and such photo-electrons upon arriving near the anode may produce additional multiplication in the gas. Under these conditions, the number of electrons produced in the discharge and collected by the anode will not be proportional to the primary ions created by the original ionizing particle whose impingement is sought to be recorded. Since such proportionality is requisite to proper operation of the proportional counter, in air counters the proportional region is limited to the region lying above the proportional threshold and below the point where photons play a significant rôle. Experimentally, it has been found that this multiplication or gas amplification in the counter containing air at atmospheric pressure extends up to approximately 10^3 , whereas higher orders of multiplication of gas amplification can be reached with polyatomic gases. The amplification factor is more critically dependent upon field intensity in the case of air counters than in the case of polyatomic gases and, therefore, air counters are more critically dependent for proper operation on the operating potential.

The behavior of the amplification factor of a proportional counter is dependent on the cathode material and construction only for such high values of voltages and amplification factors that photons are produced. Since as above stated an air proportional counter will not operate properly in such a region in any event, the material and structure of the cathode, aside from its effect on

field distribution, may be considered unimportant.

Air counters possess relatively high resolution, i. e., better than 10^{-5} seconds.

In air counters heretofore employed, it has been thought that since the ionization medium is air at atmospheric pressure no window should be required, and a metallic screen has been used as all or a portion of the cathode. But, it has been found that such designs have the disadvantage of the entry of dust into the high field regions and consequent spurious counting. It is thus imperative that there be introduced a barrier for dust which is nevertheless adapted to transmit alpha particles without substantial absorption. The best material for the dust barrier window has been found to be sheets of nylon film approximately 0.2 mil thick. The window of thin material such as nylon has been found to require a conducting coating of, for example, graphite in order to prevent the collection of electrostatic charge and consequent spurious counting. Of course, a compromise must be made between maximizing the conductivity of the coating and minimizing the particle energy absorption of the coating. It has been found that a satisfactory coating may have a resistance from the center of the window 48 to the frame 46 of the order of 1,000 to 10,000 ohms, the measurement being made by measuring the resistance between the frame 46 and a coin such as a dime placed at the center of the window 48. The coating should, of course, be as uniform as possible, and is preferably of evaporated colloidal graphite.

In operating a proportional counter filled with air at atmospheric pressure and being sufficiently open to the atmosphere so that pressure inside and outside the counter is substantially the same, it is obvious that the characteristics of the counter, which are dependent upon the pressure of the gas, will vary from day to day in accordance with the variations in ambient atmospheric pressure. Experimentally, it has been found that with counters using 1 mil diameter center-wires the shift in threshold potential in response to an atmospheric pressure change of 1 cm. Hg (the maximum daily fluctuation of atmospheric pressure in most locations) is approximately 15 to 20 volts, the normal operating potential being in the neighborhood of 2200 volts. This shift is linear over a range of at least 20 cm. Hg in the vicinity of sea level at atmospheric pressure. It has been found that in any given location the shift in operating characteristics due to atmospheric pressure changes can be virtually disregarded when the counter is incorporated in instruments for alpha particle and proton surveying and detection, which do not require extreme accuracy. At room temperatures, it has been found that there is approximately a 1 per cent change in the counting rate of the counter with a 1° F. change in temperature.

A thin window of, for example, nylon has a fairly high permeability to water vapor. The water vapor content of air changes from time to time and, therefore, it is important to understand how air counters such as illustrated in the drawing may behave at high relative humidities. All counters, irrespective of how they are prepared, show no effect up to 60-70 per cent relative humidity. Above this value counters having dirty or scratched insulators, which are preferably of polystyrene, will show a peculiar spurious counting effect similar to that appear-

ing in a counter with a high background, except that the counts are somewhat periodic rather than random in occurrence. Counters with fairly clean insulators may show the effect above 85 per cent relative humidity. It has been found that the best performance in this regard is obtained when the insulators are molded with proper precautions as to cleanliness rather than being machined. It is, of course, desirable that the surface leakage paths on all insulators between the anodes and cathodes be maximized in length. In the illustration of the drawing, the gaps 22 and the illustrated tapering of the insulating posts 28 serve this purpose.

The counter illustrated in the drawing is of the flat type which has the maximum effective area in making contamination surveys on flat surfaces. A general criterion for the proper design of the counter is that the distance between the center-wires be approximately twice the distance between the parallel plates which constitute the cathode. It has been found that such dimensions produce a satisfactory field distribution in such a counter without requiring the use of a large number of center-wires.

The counter illustrated in the drawing is only one embodiment of the present invention. Persons skilled in the art will readily devise other proportional counters embodying the teachings of the invention and will readily adapt some of the features above disclosed to devices other than proportional counters.

What is claimed is:

1. In an electron discharge device, in combination: an electrode comprising a conducting wire of uniform diameter having two ends, and end portions having transverse dimensions greater than the diameter of said wire, the respective ends of said wire being substantially integral with said end portions; and supporting members at each end of the electrode having apertures therethrough adapted to receive said wire, said apertures being open at the periphery thereof to permit peripheral introduction of the wire into the apertures and having at least one transverse dimension smaller than a transverse dimension of the respective end portion; the wire extending through the apertures and the end portions abutting against the outer surface of the respective supporting members, so that the electrode is firmly supported but readily replaceable.

2. In an electron discharge device, in combination, an electrode comprising a wire having a central portion of uniform diameter and two end portions of larger diameter than said central portion, two spaced support means having apertures therein larger than said central portion but smaller than said end portion, said apertures being open at the periphery thereof to permit peripheral introduction of the wire into the apertures, said wire extending through said apertures, and means for springily mounting at least one of said support means so as to exert tension on said wire.

3. A proportional counter comprising, in combination, a plurality of electrodes, an ionizing medium consisting of air at atmospheric pressure, and an enclosure surrounding said electrodes and said ionizing medium, said enclosure being impermeable to dust of the ambient air but having at least a portion permeable to alpha particles.

4. A proportional counter comprising in combination, a plurality of electrodes, an ionizing

medium consisting of air at atmospheric pressure, an enclosure surrounding said electrodes and said ionizing medium, and a window in said enclosure comprising a sheet of nylon less than 0.5 mil in thickness, said window being impermeable to dust of the ambient air.

5. A proportional counter comprising, in combination, a conducting center-wire electrode, a conducting wall electrode impermeable to dust and an ionizing medium between said electrodes, said ionizing medium consisting of air at atmospheric pressure and said conducting wall electrode consisting at least in part of a thin membrane of non-conducting material having on at least one side thereof a thin coating of a conducting material, said membrane and coating being permeable to alpha particles but impermeable to dust.

6. A proportional counter in accordance with claim 5 wherein said membrane consists of sheet nylon less than 0.5 mil thick and said coating comprises evaporated colloidal graphite.

7. The apparatus of claim 1 wherein at least one of the supporting members is springily mounted to exert tension on the wire.

8. The apparatus of claim 1 wherein at least one of the supporting members comprises a helical spring having at the end thereof a substantially circular hook constituting said peripherally open aperture.

9. The apparatus of claim 8 wherein the end portion of the electrode is substantially in the form of a sphere.

10. A proportional counter comprising in combination, a conducting center wire electrode, a conducting wall electrode impermeable to dust, and an ionizing medium between said electrodes, said ionizing medium consisting of a gas at substantially atmospheric pressure, and said conducting wall electrode consisting at least in part of a sheet of nylon less than 0.5 mil thick having on at least one side thereof a thin coating of conducting material, said nylon sheet and coating being permeable to alpha particles but impermeable to dust.

11. A proportional counter comprising in combination, a conducting center wire electrode, a conducting wall electrode impermeable to dust, and an ionizing medium between said electrodes, said ionizing medium consisting of a gas at substantially atmospheric pressure and said conducting electrode consisting at least in part of a thin membrane of non-conducting material having on at least one side thereof a thin coating of colloidal graphite, said membrane and

coating being permeable to alpha particles but impermeable to dust.

12. A counter having a plurality of electrodes, an ionizing medium, an envelope surrounding at least one of the electrodes and the ionizing medium, and a window in the envelope permeable to radiation, characterized by the improvement wherein the window consists of a sheet of nylon less than 0.5 mil thick coated with colloidal graphite.

13. A proportional counter comprising, in combination, a plurality of electrodes, an enclosure surrounding said electrodes, a window in said enclosure, said window consisting of a thin membrane permeable to alpha particles and impermeable to dust, an ionizable gas within the enclosure, and means for maintaining the gas at a pressure approximately the same as the pressure exterior of the enclosure.
